DESIGN FOR A NAPKIN DISPENSER

Samuel N. Hope, Wauwatosa, Wis., assignor to Griffith-Hope Company, West Allis, Wis., a corporation of Wisconsin

Application March 26, 1934, Serial No. 51,192

Term of patent 3½ years

To all whom it may concern:

Be it known that I, SAMUEL N. HOPE, a citizen of the United States residing in Wauwatosa, in the county of Milwaukee and State of Wisconsin, have invented a new, original, and ornamental Design for Napkin Dispensers, of which the following is a specification, reference being had to the accompanying drawing, forming part thereof.

In the drawing,

Fig. 1 is a perspective view of a napkin dispenser, showing my new design, the dotted lines representing the conventional outline of the dispenser;

Fig. 2 is a sectional view thereof on the plane of line 2—2 of Fig. 1, and

Fig. 3 is a transverse sectional view thereof on the plane of line 3—3 of Fig. 1.

I claim:

The ornamental design for a napkin dispenser, as shown and described.

SAMUEL N. HOPE.
